G. W. WHITEMAN

RAIL FASTENING

Filed Oct. 1, 1923

Inventor:
George W. Whiteman,

By Murray Boyer
Attorney.

UNITED STATES PATENT OFFICE.

GEORGE W. WHITEMAN, OF PHILADELPHIA, PENNSYLVANIA.

RAIL FASTENING.

Application filed October 1, 1923. Serial No. 665,744.

To all whom it may concern:

Be it known that I, GEORGE W. WHITEMAN, a citizen of the United States, and a resident of Philadelphia, Pennsylvania, have invented certain new and useful Improvements in Rail Fastenings, of which the following is a specification.

My invention relates to rail fastenings and comprises certain improvements in removable clips designed more particularly for use in connection with metallic ties for securing rails thereto, said clips being angularly adjustable with respect to the ties so that lateral adjustment of the rails with respect to such ties, when wear upon such rails requires such adjustment, can be readily effected.

The usual practice heretofore has been to secure railroad rails to metallic ties by means of bolts passing through the tie, such bolts having a portion engaging the flange of the rail, or holding rail-flange-engaging elements in place. As may be readily understood, such bolts are subject to very severe shearing strain and one object of my invention is to provide an improved construction whereby I am enabled to increase the resistance to shear strains to which these rail securing bolts are subjected.

My improved tie is of channel shape throughout, preferably with the central portion of the top web removed and the side web outwardly flared adjacent to the portion over which the rails lie. The top web of the tie is apertured for the reception of bolts or other rail securing elements at each end of the tie.

The apertures formed in the top web of the tie are rectangular in contour and may be square or oblong and the bolts which pass through the same are provided with similarly shaped shank portions, rectangular or square as the case may be, substantially fitting said apertures; such bolts occupying a fixed position with respect to the tie, and being held against turning.

These bolts constitute an abutment for the rail-engaging clips mounted upon the same, which clips have an elongated aperture for the passage of the cylindrical portion of the bolt and a groove on the under side of the same receiving that portion of the rectangular or squared shank of the bolt which projects above the surface of the tie; such clips being movable on such rectangular portion

of the bolt diagonally with respect to the longitudinal axis of the rail within the limits of the aperture through the clip when being moved into operative engagement with the rail in the adjusted positions of the latter.

After any adjustment of the rail, the clips may be anchored to the respective bolts and the tie by means of nuts and special washers interposed between the nuts and the clips; the under face of such washers and the upper faces of the clips being serrated and the serrations of the clips matching the serrations of the washer when the two are brought into holding engagement maintaining the clips in fixed position with respect to the fixed bolts.

The rectangular or squared apertures formed in the top web of the ends of the tie are set in staggered relation as indicated, so that clips disposed on opposite sides of the rail may occupy the proper relative position with respect to said rail flanges. The clips, which are arranged to move diagonally with respect to the rails are provided with a wall portion parallel to the rail flange, with a lip adjacent thereto to overlie the flange.

These and other features of my invention are more fully set forth and described hereinafter; reference being had to the accompanying drawings, in which:

Fig. 1, is a plan view of a metallic tie constructed in accordance with my invention, showing a series of rail holding clips in place.

Figs. 2 and 3, are cross sectional views of the tie, taken on the lines II—II, and III—III, Fig. 1.

Fig. 4, is a diagrammatic view showing arrangements of apertures in the tie.

Fig. 5, is a plan view of one of the rail-engaging clips on an enlarged scale.

Figs. 6 and 7 are cross sectional views, on a larger scale, taken on the lines VI—VI and VII—VII, Fig. 5, and

Fig. 8, is an inverted perspective view of one of the improved rail-engaging clips which I employ, and the bolt associated therewith.

Quite a feature of my present invention is the simplified form of means which I provide whereby railroad rails may be properly secured to metallic ties.

In the drawings, Fig. 1 shows a metallic tie of channel form, having a top web 1 and side webs 2. Such tie may be made of any

suitable form of commercial channel bars. To lighten the tie, and to provide a ballast receiving pocket through which the ballast may be properly tamped, the central portion 5 of the top web of the rail may be removed as indicated at 3. I may also flare the side webs 2, as indicated at 2^a, in Figs. 1 and 2, whereby an increased base at the rail supporting portions is provided. The top web 10 at the ends of the tie is provided with bolt apertures 4, disposed diagonally with respect to the longitudinal axis of the tie.

The rails supported by the tie are indicated at 5, and these rails are secured to the tie by means of a special form of clip and retaining bolt therefor, more particularly shown in Figs. 5, 6, 7 and 8. The clips made in accordance with my present invention comprise a body portion 6, substantially 20 wedge-shaped in contour, having an elongated aperture 7 therein, while the under side of the body portion is grooved as indicated at 8, in line with the paralleling walls of said aperture. One external face of the 25 clip, indicated at 9, parallels the walls of the groove 8, and these walls lie diagonally with respect to the opposite external face 10 of the clip, which when applied to the tie lies parallel to the flange of the rail. The 30 upper portion of the clip extends over this face 10, to provide a lip 10^a, overlying the flange of the rail. The upper surface or top of the clip is serrated, as indicated at 11, and such serrations may be at right angles to 35 the longitudinal axis of the rail, or at right angles to the longitudinal axis of the aperture 7 formed in the clip.

The bolts 15, employed for the purpose of securing the clips in place are provided with 40 a large head 15^a, which may be of the usual rounded type, from which extends a rectangular or squared shank portion 16, of such length that when disposed in proper position in one of the apertures 4 of the tie, it 45 projects above the latter to a considerable extent. From this shank portion 16, which is always of angular contour, rectangular or square, the cylindrical threaded portion of the bolt 17 extends, to which a nut 18 may 50 be applied in the usual manner.

That portion of the squared or rectangular shank 16 of the bolt which projects above the top web of the tie fits the groove 55 on the under side of the clip and constitutes an abutment for the latter; such clip being movable on such bolt shank within the limits of the elongated slot or aperture 7, therein, and by reason of the position of the rectangular shank of the bolt in the tie, such movement 60 of the clip is diagonal with respect to the longitudinal axis of the rail. To hold the clips in their adjusted position, I employ a special type of washer 19, having a serrated under face 20 which fits the serrations formed in the top of the clip, and

these washers are held in place by the nuts 18. As the bolts occupy a fixed position, the clamping of the washers in place holds the clips in proper position with respect to the rail.

When it is necessary to move either one of the rails laterally to compensate for wear upon the same, the nuts in engagement with the clip-holding bolts are removed or loosened and the washers are lifted so as to permit movement of the clips with respect to the bolts. If the adjustment is to the right with reference to the rail at the left hand side of the tie as shown in Fig. 1, the clip at the right hand side of the rail flange is 70 moved in the direction of the arrow, a slight distance, as indicated by dotted lines, sufficient for the desired movement of the rail, and the latter is also moved in the new position, as indicated by dotted lines. Then this clip may be secured in place. Then the clip at the left hand side of the rail is moved so that its lip overlies the rail flange in the new position of the latter, and the washer is dropped into place; the serrations on the under side of the same finding a fresh seat in the serrated top of the clips, the nut is screwed down, and then the rail is held in the desired adjusted position.

As will be understood, any lateral thrust 95 of the rail is taken by the rectangular portion of the bolt, which extends above the top web of the tie and fits into the recess or groove in the under side of the clip.

In use, each rail will be held to the tie by 100 a pair of clips, and by providing a series of rectangular apertures set in the staggered relation and position illustrated, provision is made for a considerable amount of adjustment to the rails.

In Fig. 4, I have shown diagrammatically, 105 a series of apertures, 4 and 4^a, formed in the top web of a tie. The apertures 4 illustrate the position for one weight of rail, while the apertures 4^a illustrate the position for another weight of rail. The line A represents the longitudinal axis of the tie and the line B, the longitudinal axis of the rail.

I claim:

1. In combination with a metallic tie having a rectangular aperture formed in its rail-supporting portion, a bolt having a portion to fit said aperture, an adjustable rail-engaging member overlying said bolt; the portion of the latter fitting the rectangular aperture in the tie projecting above the web of the same and engaging parallel walls formed on the under side of said rail-engaging member and the latter being provided with an elongated aperture whereby it is capable of movement with respect to the rectangular shank of the bolt and in line therewith, and means for confining said rail-engaging member in various positions with respect to said bolt.

2. In combination with a metallic tie having a rectangular aperture formed in its top web or rail-supporting portion; said aperture being disposed diagonally with respect to the longitudinal axis of the tie, a bolt having a portion to fit said aperture, an adjustable rail-engaging member overlying said bolt; the portion of the latter fitting the rectangular aperture in the tie 65
- 5 10 projecting above the web of the same and engaging parallel walls formed on the under side of said rail-engaging member and the latter being provided with an elongated aperture whereby it is capable of movement with respect to the rectangular shank of the bolt and in line therewith; such movement being in a line diagonal to the longitudinal axis of the rail and means for confining 70
- 15 said rail-engaging member in various adjusted positions with respect to said bolt. 75
3. In combination with a metallic tie having a series of rectangular apertures formed in its rail-supporting portion at each end thereof and disposed in staggered relation, 80
- 25 a series of bolts each having a rectangular portion to fit said aperture, adjustable rail-engaging members overlying said bolts; the portion of the latter fitting the rectangular apertures in the tie projecting above the web 85
- 30 of the same and engaging parallel walls formed on the under side of said rail-engaging members and the latter being provided with elongated apertures whereby they are capable of movement with respect 90
- 35 to the rectangular shanks of the bolts and in line therewith, and means for confining said rail-engaging members in position. 95
4. In combination with a metallic tie having a rectangular aperture formed in its 100
- 40 rail-supporting portion, a bolt having a portion to fit said aperture, an adjustable rail-engaging member overlying said bolt; the portion of the latter fitting the rectangular aperture in the tie projecting above the web 105
- 45 of the same and engaging parallel walls formed on the under side of said rail-engaging member and the latter being provided with an elongated aperture whereby it is capable of movement with respect to the rectangular shank of the bolt and in line therewith; said rail-engaging member having a serrated upper surface, and means for confining 110
- 50 said rail-engaging member in position including a washer fitting the bolt and having complementary serrations to engage the serrated surface of the rail-engaging member, and a nut. 115
- 55
5. In combination with a metallic tie having a rectangular aperture formed in its top web or rail-supporting portion; said aperture being disposed diagonally with respect to the longitudinal axis of the tie, a 120

In witness whereof I have signed this specification.

GEORGE W. WHITEMAN.
